PICTURE SLIDE FEEDING MECHANISM

Max E. Blumenstein, Hyattsville, Md.

Application August 23, 1945, Serial No. 612,146

2 Claims. (Cl. 88—28)

1

This invention relates to an improved picture slide feeding mechanism, and has for its general object to provide a simple, practical, inexpensive and reliable finger-operable mechanism for feeding picture slides successively to a viewing position.

While the picture slides may be supplied by hand to the mechanism to be fed by the latter to the viewing position, a magazine preferably is provided to contain the slides and in this connection a special object of the invention is to provide a projectable and retractable member for feeding the slides successively from the magazine to the viewing position and to provide a latch for cooperation with said member to insure proper successive feeding of the slides.

With the foregoing and other objects in view, which will become more fully apparent as the nature of the invention is better understood, the same consists in a mechanism for the purpose stated embodying the novel features of construction, combination and arrangement of parts as will be hereinafter more fully described, illustrated in the accompanying drawing and defined in the appended claims.

In the accompanying drawing, wherein like characters of reference denote corresponding parts in the different views:

Figure 1 is a vertical section through a mechanism constructed in accordance with one practical embodiment of the invention.

Figure 2 is a section on the line 2—2 of Figure 1 through the mechanism.

Figure 3 is a section on the line 3—3 of Figure 1; and

Figure 4 is a section on the line 4—4 of Figure 2.

Referring to the drawing in detail, A designates a portion of the casing of a picture slide viewing apparatus and B designates, generally, a picture slide slideway which may be of any suitable construction and which may be disposed in any suitable manner relative to said casing A.

In the present instance, the slideway B is illustrated as being disposed vertically within the casing A adjacent to the front wall 10 of said casing, and as being formed by a pair of vertically disposed, spaced apart, parallel rails 11, 11' fastened against the front face of a vertical wall or panel 12 suitably mounted in the casing A adjacent to the front wall 10 thereof, said rails 11 and 11' being suitably grooved or channeled at their adjacent sides, substantially as shown, to accommodate the side marginal portions of the picture slides.

2

Adjacent to and extending parallel to the slideway B is another slideway, designated generally as C, for a member 13 for use in advancing picture slides through the slideway B. As in the case of the slideway B, this slideway C may be of any suitable construction and is illustrated in the present instance as being comprised by the rail 11 and another rail 14 disposed in spaced, parallel relationship to said rail 11 and suitably fastened to the wall or panel 12, the adjacent sides of said rails 11 and 14 being grooved or channeled to accommodate the side marginal portions of the member 13.

In the wall or panel 12, between the rails 11 and 11' is an opening 15 with which the picture slides, designated as S, are to be aligned, and when a picture slide is aligned with said opening it is in a position to be viewed or, in other words, is in the viewing position.

Within the casing A is an electric lamp 16 or any other suitable means for illuminating a picture slide disposed in the viewing position, while in front of said casing, is a lens, or a lens system, designated as 17, through which a picture slide disposed in the viewing position is to be viewed and which is effective to magnify the picture on the slide.

Picture slides may be fed by hand to the slideway B to be advanced by the member 13 to the viewing position. Preferably, however, a magazine 18 is provided to contain a number of picture slides to be fed successively to the slideway B for advance therethrough by the member 13 to the viewing position. The magazine 18 is located suitably in advance of the viewing position, in alignment with the slideway B, and has its outlet end open and disposed adjacent to said slideway. The picture slides S are disposed in face to face relationship in said magazine and are urged toward the slideway B in any suitable manner. For example, the magazine may be inclined so that the picture slides will gravitate into the slideway B, or any suitable yieldable means may be employed to urge the slides toward said slideway 45 regardless of whether the magazine is or is not inclined. In any event, the arrangement in this respect is such that the slides are fed individually and successively from the magazine to the slideway B, a new slide entering said slideway whenever the last-fed slide is slid therealong from its position in registration with the open or outlet end of the magazine 18. To permit the slides to leave the open end of the magazine 18 and enter the slideway B, the flange portions of the 55 rails 11, 11' in alignment with said magazine may

be suitably cut away as indicated at 19. Alternatively, the entrance end of the slideway B may be disposed below the bottom of the magazine 18 if the slideway is disposed vertically and the slides are to be fed downwardly, or the said entrance end of said slideway may be disposed to either side of the magazine if the slideway is disposed horizontally and the slides are to be fed laterally.

The member 13 carries a finger 20 which extends into the slideway B for engagement with the trailing edge of a slide S, as regards the direction of advance of the slide through said slideway, so that by shifting said member in the direction of advance of the slide the latter is advanced along said slideway. Suitable yieldable means, such as a spring 21, is provided to retract the member 13 against a suitable stop 22, and when said member is positioned against said stop the finger 20 is disposed in engagement with or is suitably spaced beyond the trailing edge of a picture slide S disposed in the slideway B in alignment with the magazine 18. From its position in engagement with the stop 22, the member 13 is slideable in the direction of advance of the picture slide an amount just sufficient to advance the picture slide to the viewing position, suitable stop means 23 being provided to prevent any further advance of said member. Consequently, if the member 13 is in its retracted position and a picture slide is disposed in the slideway B in alignment with the magazine 18, projection or advance of said member 13 until it is stopped by the stop means 23 will result in the picture slide being advanced exactly to the viewing position.

In depth, the slideway B is approximately equal to the thickness of a picture slide S. Therefore, not more than a single picture slide may enter said slideway from the magazine 18 at any given time. In other words, before another picture slide may enter said slideway from said magazine, a picture slide in said slideway must be advanced beyond a position in alignment with said magazine. In this connection, it is desirable to prevent feeding of a picture slide from the magazine 18 into the slideway B at any time except when the member 13 is retracted to avoid interference with retraction of said member and to insure that when a picture slide is fed from said magazine into said slideway, the finger 20 will be disposed beyond the trailing edge of the picture slide so as to be effective to advance the same in response to projection of said member 13. As a picture slide is being advanced from a position in alignment with the magazine 18, the finger 20 moves toward the leading edge of the next slide in said magazine and prevents the leading edge portion of said next slide from being fed to the slideway B. At the same time, a suitable latch element 24 acts to prevent the trailing edge portion of the said next picture slide from being fed from said magazine to said slideway. The said next picture slide thus effectively is prevented from being fed to the slideway B until the member 13 is retracted. The latch element 24 may be either slideable or pivoted. In the present instance, it is shown as being pivoted. In any event, it is urged in the direction of advance of the slides S against a suitable stop 25 by a suitable spring 26. Moreover, it is located so that when it is disposed against said stop 25, a suitable portion thereof overlies the trailing edge portion of the next picture slide to be fed from the magazine 18 and thus prevents feed-

ing of such slide from said magazine. The location of said latch element also is such that a suitable part thereof is engaged by the finger 20 or some other suitable part of the member 13 when said member is retracted and so that the final portion of retractile movement of said member 13 is effective to shift the same away from the stop 25 to a position to release the next picture slide to permit the same to be fed from the magazine 18 into the slideway B. Accordingly, upon retraction of the member 13, a new picture slide enters the slideway B from the magazine 18 for advance by the member 13 when said member subsequently is projected, and as a result of initial projection of said member 13 the latch element 24 moves against the stop 25 and into overlying relationship to the trailing edge portion of the next picture slide is illustrated by dotted lines in Figure 2, to hold the next slide in the magazine 18 until said member 13 again is retracted.

The slideway B may be of a length to contain either several picture slides S or only two picture slides, one in alignment with the magazine 18 and the other in the viewing position in alignment with the opening 15. In any event, the picture slides are disposed in edge to edge relationship in the slideway B so that advance of a picture slide by the member 13 results in advance of all slides in said slideway. Moreover, the disposition of the magazine 18 relative to the viewing opening 15 is such that each time a new slide enters the slideway B from the magazine 18 and is advanced by the member 13, a picture slide in the viewing position is advanced and discharged into a suitable receptacle 27, and a new picture slide is advanced to the viewing position.

To adapt the member 13 for finger projection, the same may be provided with a suitable finger-engageable element 28 which may be carried by the outer end portion of an arm 29 extending from said member through a slot 30 in the front wall 10 of the casing A, while in order to hold the picture slides against undesirable accidental sliding movement in the slideway B, said slideway may be provided with suitable leaf springs 31 or other suitable friction means for engagement with marginal portions of the picture slides.

From the foregoing description considered in connection with the accompanying drawings, it is believed that the construction and operation of the present mechanism will be clearly understood and its advantages appreciated. It is desired to point out, however, that while only a single structural embodiment of the invention has been illustrated and described, the same is readily capable of specifically different structural embodiments within its spirit and scope as defined in the appended claims.

I claim:

1. A mechanism for feeding picture slides from a magazine to a viewing position, said mechanism comprising a slideway for the slides, a magazine to contain the slides, said magazine being disposed to have slides fed therefrom successively into said slideway, means to insure feeding of slides successively from said magazine to said slideway, a member mounted for sliding movement longitudinally relative to said slideway between retracted and projected positions, a projection on said member for engagement with a slide in said slideway when said member is in its retracted position and the slide is aligned with said magazine and disposed in advance of the viewing

position so that sliding of said member to its projected position is effective to advance the slide to the viewing position, said projection being engageable with the next slide to be fed from the magazine to the slideway to prevent feeding of the same until said member has been projected and subsequently retracted, stop means to stop slide-advancing sliding movement of said member when a slide being advanced thereby reaches the viewing position, yieldable means for retracting said member, means for finger engagement to effect projection of said member, and a latch yieldably urged to overlie a portion of the next slide to be fed from said magazine and for cooperation with said projection to prevent feeding from said magazine to said slideway of the said next slide to be fed from said magazine to said slideway during advance by said member to the viewing position of the slide last fed from said magazine to said slideway, said member being effective upon retraction thereof to move said latch to release the next slide for movement from said magazine into said slideway for advance to the viewing position when said member again is projected.

2. A mechanism as set forth in claim 1 in which the latch is pivoted for swinging movement between slide-releasing and slide-holding positions.
